[57] CLAIM

The ornamental design for an electronic hemodynamometer, as shown and described.

DESCRIPTION

FIG. 1 is a front perspective view of the electronic hemodynamometer showing our new design;
 FIG. 2 is a top plan view thereof;
 FIG. 3 is a front elevational view thereof;
 FIG. 4 is a rear elevational view thereof;
 FIG. 5 is a left side elevational view thereof;
 FIG. 6 is a right side elevational view thereof; and
 FIG. 7 is a bottom plan view thereof.
